UNITED STATES PATENT OFFICE.

WILLIAM H. BOWMAN, OF SOUTH SOLON, OHIO, ASSIGNOR OF ONE-HALF
TO ALEXANDER B. LUKENS, OF SAME PLACE.

ATTACHMENT FOR CORN-PLANTERS.

SPECIFICATION forming part of Letters Patent No. 378,569, dated February 28, 1888.

Application filed September 20, 1887. Serial No. 250,180. (No model.)

To all whom it may concern:

Be it known that I, WILLIAM H. BOWMAN, of South Solon, in the county of Madison and State of Ohio, have invented a new and Improved Attachment for Corn-Planters, of which the following is a full, clear, and exact description.

My invention relates to a check attachment for corn-planters, and has for its object to provide a means whereby a reliable check may be attached to any style of corn-planter, and wherein the said attachment may also be used for drilling the corn; and the further object of the invention is to provide a means whereby in irregularly-shaped fields the checking may be accomplished as regularly as in rectangular fields.

The further object of the invention is to construct a reliable check-row attachment which will be cheap in construction and reliable and effective in operation.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a plan view of the attachment secured to a corn-planter, and Fig. 2 is a transverse section on line $x-x$ of Fig. 1. Fig. 3 is a side elevation of the attachment, and Fig. 4 is a plan view of the clearance and regulating bar. Fig. 5 illustrates a modification of the adjusting-bar; and Fig. 6 is a detail view of the marker, illustrating the application thereto of an adjustable gage.

In carrying out the invention the body of the attachment consists of a beam, A, the forward end of which is recessed at each side to a point at the rear of the center to form the tongue or reduced portion A'.

In the beam, transversely to the same and to the rear of the tongue, a shaft, a, is journaled, carrying at each end a marking-bar, B, which bars or markers are secured centrally to the shaft a, turning therewith, having their extremities pointed and preferably curved in opposite directions. The markers may, however, be made straight, as shown in Figs. 5 and 6, without departing from the spirit of my invention.

Upon the inner side of each marker, near opposite ends, pins b are attached, and the beam A, at the rear of the shaft, is provided with aligning recesses b' in the opposing edge, through which the pins b pass when the markers, which are secured parallel upon the shaft, are revolved.

A short bar, B', is made to project centrally from each edge of the markers at right angles thereto, the said bar being preferably in one piece, whereby substantially the shape of an X is imparted to the markers, having one leg shorter than the other. The purpose of the bar B' is to afford a grip for the hand, so that in the event the markers are thrown out of check from any cause they may be turned and placed in registry again.

A bar, C, is attached transversely the rear upper end of the body-beam A. Extending out from each side edge and upon the bar C scraper-blocks C' are adjustably secured by bolts or otherwise to project forward in alignment with the axis of the markers. Each of the scraper-blocks is provided with a V-shaped recess or slot, C'', in its forward end, through which recess the ends of the markers are adapted to pass, as illustrated in Fig. 1.

At each side of the tongue A', about centrally the same, levers D and D' are respectively pivoted by one pivotal pin, d, passing through the tongue and levers. Both ends of the levers are unattached, the rear ends extending nearly to the shoulder produced in the body-beam by the side recesses forming the tongue, at which point the levers are alternately acted upon by the pins b, secured to the markers, for a purpose hereinafter specified.

The forward ends of the levers are adapted to bear against the under face of the longitudinal members e e' of an inverted-T-shaped rocking bar, E, pivoted in bearings e'', slightly above the tongue, centrally the lower end. The under face of the rocking bar is convexed, and the upper end of the vertical member is provided with a series of apertures, f, in one of which apertures a link, F, is secured, the other end of said link being adapted for attachment to the sliding bar of the seed-boxes of a corn-planter, to reciprocate the same.

The attachment is preferably attached to a planter through the medium of a beam, F', attached at right angles to the forward end of the tongue, the said beam being detachably

secured to the body of the planter in any approved manner.

Beneath the tongue A', near the forward end, a drag, H, is pivoted, consisting of a body, 5 h, adapted to rest upon the ground, provided with a vertical beveled projection, h', integral with its forward end, upon the outer beveled face of which projection fenders H' are secured, constructed of metal plates placed at 10 an angle to each other, having their contiguous edges united to cover the outer pointed edge of the projection h', and their outer faces made concave or curved inward centrally and outward at the projecting ends. Upon the 15 upper surface of the body h a lug, k, is cast or otherwise formed, provided with a set-screw, k', in its upper end, and the body is pivoted to the tongue by an upwardly-inclined arm, K, integral with and extending outward from 20 the projection h', as illustrated in Fig. 3.

The object of the drag is twofold. By means of the set-screw k', upon which the body-beam A rests, the said beam may be vertically adjusted, and the depth that the markers shall 25 penetrate the ground be thereby regulated. The drag, also, by means of the levelers, clears and smoothes the ground in advance of the markers. If found desirable, the set-screw upon the drag may be dispensed with, and the 30 adjustment of the markers be effected by adjustably attaching a bar, M, to the rear of the planter, as shown in Fig. 5, which bar is made to pass beneath the body-beam A and engage its under surface. To prevent the markers 35 from sinking too deep, a series of apertures, m, may be made longitudinally at each end, and pointed centrally-apertured slats M' are transversely attached to the markers a suitable distance from their ends, through the medium of the apertures m and bolts or other 40 suitable adjustable fastening devices, as shown in Fig. 6.

In operation, as the planter having the attachment secured thereto is driven along the 45 markers B revolve, and the pins b, acting upon the levers D and D', alternately depress their rear ends, causing their forward ends to raise either the member e or e' of the rocking bar E, which, through the link-connection aforesaid, reciprocates the drop-bar of the planter 50 and causes the seed to flow down into the drill simultaneously with each check.

It will be observed that should the wheel 55 of the planter slip forward or backward, or run over clods of hard dirt, the deviation will not have any effect upon the markers, and that should the marking-wheel get out of check it only becomes necessary to slightly raise the beam A and turn the wheel back or forth to 60 register with the mark last made.

In irregularly-shaped fields when the irregularities are reached the attachment is unhooked from the planter, set in the last mark made, and pulled back by hand to where it is desired 65 to commence checking again, whereupon it is reattached to the planter. When the attach-

ment is run backward, it is obvious that the revolving markers will have no effect upon the seed-drop bar, as the pins readily pass the levers.

When the drag H is employed and the machine is upon the road, the said drag may be hooked to the planter in like manner as a cutter-bar upon a mowing-machine is disposed of.

Having thus fully described my invention, 75 what I claim as new, and desire to secure by Letters Patent, is—

1. The ground-marking attachment for corn-planters, wherein the marker proper consists of a single centrally-hung revolving bar which 80 acts upon the ground at its ends, marking it at intervals, substantially as set forth.

2. In a ground-marking attachment for corn-planters, the marker proper consisting of a single centrally-hung revolving bar having its 85 ends pointed and curved in opposite directions, substantially as specified.

3. In a ground-marking attachment for corn-planters, the centrally-hung revolving marking-bar provided with pins or projections near 90 relatively-opposite ends and having their ends adapted to more or less enter and mark the ground, in combination with actuating-levers hung upon the bar carrying the said marking-bars, and which levers operate the corn-dropping-slide-actuating mechanism, substantially 95 as set forth.

4. In an attachment for corn-planters, the combination, with the bar adapted to be applied to the frame of the planter and carrying 100 side levers actuating the corn-dropping-slide-actuating mechanism, of the ground-markers supported upon said bar and provided with adjusting-apertures to receive stops to regulate the depth of penetration of the arms of 105 the markers, substantially as set forth.

5. The combination, with the bar carried by the corn-planter frame and carrying side levers actuating the corn-slide-operating mechanism, and markers provided with pins acting 110 upon said levers, of the drag-bar pivoted or connected to the aforesaid bar and carrying a supporting and adjusting screw, substantially as set forth.

6. The combination, with the bar adapted to 115 be applied to the planter-frame and carrying side levers actuating the corn-slide-actuating mechanism and operated upon by pins projecting from markers, of a supporting and adjusting bracket, substantially as specified.

7. The combination, with the bar adapted to be applied to the frame of the planter and carrying side levers actuating the corn-slide-operating mechanism, and the markers acting upon said levers, of the bifurcated scrapers 125 adjustable upon the said planter-frame and adapted to receive the markers, substantially as set forth.
